ELLERY A. WALKER, OF HYANNIS, MASSACHUSETTS.

Letters Patent No. 101,792, dated April 12, 1870.

IMPROVEMENT IN PISTON-PACKING.

The Schedule referred to in these Letters Patent and making part of the same.

To all to whom these presents shall come:

Be it known that I, ELLERY A. WALKER, of Hyannis, in the county of Barnstable and State of Massachusetts, have made an invention of a new and useful Manufacture of Pistons for Steam-Enginey; and do hereby declare the following to be a full, clear, and exact description thereof, due reference being had to the accompanying drawings making part of this specification, and in which—

Figure 1 is an elevation;

Figure 2, a vertical section; and

Figure 3, an end view, with the outer cap removed, of a piston embodying my improvements.

The class of pistons upon which this invention is founded is that known as "sectional ring-packing" pistons, or those in which a series of metallic rings or sections of rings are employed, and which, by their pressure against the interior of the cylinder of the engine, serves to prevent clandestine passage of steam between the two.

Previous to the origin of the improvements herein to be described, these sectional rings have been expanded in two ways: one by the direct pressure of the steam, admitted behind them in small quantities from the cylinder, and the other by the pressure of springs behind them.

The force of the steam has been found to exert too sudden and injurious action upon the cylinder, and this mode of expanding the sectional rings has been generally abandoned.

The action of the springs is subject to changes in power, owing to the reduction of the periphery of the packing-rings under wear, and, as pistons have heretofore been produced, must be frequently "set out" by means of set-screws applied to them for the purpose, this act necessitating frequent removal and dismemberment of the piston.

It is well known to persons accustomed to the action of steam-engines, that the tendency of the piston to "tilt" in the cylinder at one extreme of its traverse, and, to some extent, both, wears such cylinder at one point in its circumference, often requiring renewed boring out, or permitting escape of steam past the piston, owing to the fact that the rings, which perform the office of packing the piston, also form its entire bearing-surface.

Attempts have been made to remedy this by the employment of a central ring of soft metal, located midway between the ends of the piston, for the purpose of "centering the piston." But when the latter "tilts," as above specified, it is the ends of the piston which are liable to wear the cylinder, and therefore a soft metal ring, arranged centrally, will not afford adequate protection.

The object I have had in view, principally, in orig-

inating this invention, which comprises the subject matter of these Letters Patent, has been to create upon the periphery of the piston, at or near each end, a bearing or supporting-surface or surfaces, which shall receive the general wear upon such piston, by this means relieving the packing-rings of this duty, which has heretofore devolved upon them, and requiring them only to preserve a tight joint between the piston and cylinder.

By effecting this result I economize, to a great and valuable extent, the unequal wear of the piston upon the cylinder, since the bearing-surfaces at each end of such piston are to be of a metal softer than that of the cylinder.

By referring to the drawings accompanying this specification and illustrating my invention, the reader will perceive that—

a represents the piston of a steam-engine cylinder, the component parts of which are shown in the head or block at *b*, the outer plates or caps at *c c*, and the sectional or split packing-rings at *d d*, such parts being produced and combined in manner substantially similar to others in use, with exceptions hereinafter stated.

In carrying out my invention, I form each of the two end caps or plates *c c*, which confine the packing-rings in place, with a circumscribing peripheral channel or groove, *e*, and I fill this channel with Babbitt or other soft metal, *f*, permitting of an excess of the same beyond the periphery of the cap, in order that it (the soft metal) alone shall come in contact with the bore of the cylinder, with the exception of the packing-rings *d d*.

These packing-rings encircle, or nearly so, the periphery of the piston-block, a shallow intervening annular chamber, *g*, being left between the two to receive a plurality of curved plate-springs, *h h*, &c., formed and disposed as shown in fig. 3 of the drawings; that is, as exerting a pressure between the piston-head *b* and the packing-rings *d d*, and forcing the latter into contact with the bore of the cylinder.

Owing to the fact that the cap-plates *c c* of the piston, or their soft metal-rings or ribs, serve to sustain the thrusts upon such piston, and maintain its proper position within the cylinder, the wear exerted upon the packing-rings is, comparatively, very slight, and no set-screws are needed to compensate for the increase in area of the annular inclosure *g* which now ensues, owing to the rapid wear upon the rings and the bore of the cylinder, and thus I avoid the present unavoidable stoppage of the engine, the loss of time, and the annoyance of removing and dismembering the piston.

As the packing-rings, combined with the piston-head in the present instance, are of one piece of metal

with the abutting ends, some means becomes necessary for preventing turning of the same about the piston-head, in order to avoid coincidence of the openings of the two.

In the drawings hereto annexed I exhibit a means of effecting this purpose, which consists in fixing upon the inner face of each ring two projections or pins, *i i*, such pins straddling a fin or rib, *j*, extending outward from the piston-head.

Although I have, in the accompanying drawings, exhibited the soft metal as a continuous ring, encircling each end plate of the piston, it may be disposed in sections, as practice has demonstrated that a bearing-surface for each end of the piston, at the top and bottom, will be sufficient.

Having described my invention, I would state that I do not claim, broadly, the formation upon the piston of a soft metal bearing-surface, but

What I claim, and desire to secure by Letters Patent, is—

The herein-described combination and arrangement of the packing-rings *d d*, springs *h h*, and end plates *c c*, the latter being provided with a soft-metal bearing, and the whole operating as hereinbefore set forth.

ELLERY A. WALKER.
